UNITED STATES PATENT OFFICE.

DWIGHT WILSON BENNETT, OF SOMERTON, PENNSYLVANIA.

BOLT-ANCHOR.

1,103,859.

Specification of Letters Patent. Patented Aug. 25, 1914.

Application filed March 17, 1813, Serial No. 754,863. Renewed July 27, 1914. Serial No. 853,447.

To all whom it may concern:

Be it known that I, DWIGHT WILSON BENNETT, a citizen of the United States, residing at Somerton, in the county of Philadelphia and State of Pennsylvania, have invented certain new and useful Improvements in Bolt-Anchors; and I do declare the following to be a full, clear, and exact description of the invention, such as will enable others skilled in the art to which it appertains to make and use the same.

This invention relates to improvements in bolt anchors.

One object of the invention is to provide a bolt anchor for concrete floors, ceilings, walls or the like having means whereby the anchor is secured to the base or frame on which the concrete is laid and which is formed in a plurality of sections thereby reducing the cost of casting the same.

Another object is to provide a bolt anchor having adjustable casing members whereby the hole in the concrete through which the bolt is engaged with and removed from the anchor is formed and kept open.

A further object is to provide a device of this character which will be simple, strong, durable and inexpensive in construction, efficient and reliable in operation and well adapted to the purpose for which it is designed.

With these and other objects in view, the invention consists of certain novel features of construction, and the combination and arrangement of parts as will be more fully described and claimed.

In the accompanying drawings: Figure 1 is a sectional view through a concrete floor showing my improved bolt anchor applied thereto and in side elevation; Fig. 2 is a similar view showing the anchor and the bolt casing or lining of the bolt hole in section; Fig. 3 is a similar view showing a bolt applied thereto for fastening an object to the floor; Fig. 4 is a top plan view of the anchor with the bolt casing removed; Fig. 5 is a horizontal sectional view of the anchor taken on the line 5—5 of Fig. 1; Fig. 6 is a similar view taken on the line 6—6 of Fig. 1; Fig. 7 is a detail perspective view of the bolt casing or lining for the bolt hole which is formed in the concrete above the anchor.

My improved bolt anchor comprises a main body portion 1 formed in two semi-

cylindrical sections 2 and 3 which are provided on their inner surfaces with bolt threads 4 and have on their outer sides series of semi-circular spirally disposed ribs 5 which when the sections are joined form a continuous spiral rib extending from the inner or upper end of the anchor to the lower end thereof. On the lower end of the sections of the anchor are formed series of radially projecting base lugs 6 which are engaged with the joists or bars of the framework on which the concrete material is laid and to which said lugs are secured by staples 7 or other suitable fastening devices. It will be noted that two of the lugs 6 are divided, one-half of each lug being formed on each section, said half lugs being brought together when the sections are assembled. The engagement of the staples 7 with the half sections of the lugs serves to fasten these lugs and the lower end of the sections together. On the sections of the anchor near their upper ends are also formed radially projecting anchoring lugs 8 which are constructed similarly to the base lugs 6 but are of less length than the latter. In the upper ends of the sections of the anchor are formed semi-circular recesses 9 which when the sections are brought together form a continuous recess which is provided for a purpose hereinafter described. In order to fasten the sections of the lugs together in operative engagement to form the anchor, I provide one of said sections with laterally extending fastening or clamping lugs 10 two of which are formed on one edge of the section near the upper and lower ends thereof, while on the opposite edge of said section midway between the ends thereof is formed a single lug. The lugs 10 are sufficiently malleable to permit them to be bent around or into engagement with the outer side of the opposing section of the anchor thereby securely clamping said sections together to form the anchor.

On the inner side of the lower ends of the sections are formed semi-circular flanges 11 which when the sections are brought together forms a continuous annular flange which provides a seat for a bottom plate or disk 12 which is engaged therewith and clamped between the sections when the latter are fastened together. The plate when thus arranged prevents the concrete or other

material from entering the lower end of the anchor and thus interfering with the proper insertion of the bolt.

In order to form a bolt hole in the concrete above the anchor and to protect the sides of the hole thus formed whereby a bolt may be readily inserted therein and engaged with the anchor, I provide a bolt casing or bolt hole lining 13 which is preferably formed of two cylindrical telescoping tubular members the outer or lower member of which has a diameter corresponding substantially with the diameter of the annular seat or recess 9 formed in the upper end of the anchor and with which said outer or lower member of the tubes is engaged as shown. The inner or upper member of the casing or lining 13 is adapted to be adjusted in the lower outer member to form a casing or lining of the desired length. By thus forming the casing or lining of two adjustably or telescoping engaged members it will be seen that the length of the casing or lining can be readily varied to accord with the thickness or depth of the concrete floor, ceiling or other structure in which the anchors are arranged. By providing the casing or lining 13 it will be seen that a hole will be formed in the upper portion of the concrete directly in line with the bore or passage of the anchor and that the sides or walls of the hole thus formed will be protected by the lining thus preventing particles of the concrete from being chipped off and falling into the anchor which would materially interfere with the insertion of the bolt in the anchor.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed.

Having thus described my invention, what I claim is—

1. A tubular bolt anchor having an annular seat near its upper end, a spiral rib formed on the outside of said anchor, and a bolt casing having engagement with said seat and adapted to form a passage through which the bolt is inserted for engagement with the anchor.

2. A bolt anchor comprising segmental interiorly threaded tubular sections having therein near their upper ends semi-circular recesses which when the sections are brought together form an annular seat, means to fasten said sections together to form the anchor, a spiral rib formed on the outer sides of said sections, and a bolt casing engaged with the seat in the upper end of said sections and adapted to form a passage through which the bolt is inserted for engagement with the anchor.

3. A bolt anchor for concrete structures comprising hollow segmental interiorly threaded sections having in their upper ends semi-circular recesses which when the sections are brought together form an annular recess, malleable clamping lugs formed on one of said sections and adapted to be bent around the opposing section whereby said sections are fastened together to form the anchor, a bolt casing formed in tubular telescopedically engaged sections adapted to be engaged with the annular seat in the upper end of said anchor and to project upwardly therefrom through the concrete, said sections being adapted to be adjusted to correspond with the thickness of the concrete above the anchor whereby a bolt hole is formed in the concrete, and a lining provided therefor by said casing.

In testimony whereof I have hereunto set my hand in presence of two subscribing witnesses.

DWIGHT WILSON BENNETT.
